UNITED STATES PATENT OFFICE.

HENRY R. LUCKOCK AND CHARLES H. TAYLOR, OF NEWARK, NEW JERSEY, ASSIGNEES TO JEWEL CUT GLASS COMPANY, OF NEWARK, NEW JERSEY, A CORPORATION OF NEW JERSEY.

DESIGN FOR A GLASS VESSEL.

42,333.

Specification for Design.

Patented Mar. 19, 1912.

Application filed December 7, 1911. Serial No. 664,517. Term of patent 7 years.

To all whom it may concern:

Be it known that we, HENRY R. LUCKOCK and CHARLES HERBERT TAYLOR, citizens of the United States, residing at Newark, in the county of Essex and State of New Jersey, have invented a new, original, and ornamental Design for Glass Vessels, of which the following is a specification, reference being had to the accompanying drawings, forming part thereof.

Figure 1 is a plan of a glass vessel, show-

ing our new design; and Fig. 2 is an elevation of the same.

We claim:

The ornamental design for a glass vessel as shown.

H. R. LUCKOCK.
CHARLES H. TAYLOR.

Witnesses:

GEO. M. BURDITT,
JAMES HAMILTON.
